UNITED STATES PATENT OFFICE.

GEORGE R. CANNON, OF GUILFORD, OHIO.

IMPROVEMENT IN SHELVINGS FOR WAGONS.

Specification forming part of Letters Patent No. **59,356**, dated November 6, 1866.

To all whom it may concern:

Be it known that I, GEORGE R. CANNON, of Guilford, in the county of Medina and State of Ohio, have invented a new and useful Improvement in Shelvings for Wagons; and I do hereby declare that the following is a full, clear, and exact description thereof, which will enable others skilled in the art to make and use the same, reference being had to the accompanying drawings, forming part of this specification, in which—

Figure 1 is a side elevation of a wagon-box with my invention applied thereto. Fig. 2 is an end elevation thereof. Fig. 3 is a plan or top view.

Similar letters of reference indicate like parts.

My invention consists, first, in the manner of securing the cross-beams to the top rails of the wagon-box, whereby each beam is applied and attached separately from the other; also, in the manner of connecting the longitudinal strips or planks to the cross-beams, whereby they can be removed separately, the whole arrangement providing a shelving for wagons, for converting the wagon into a suitable vehicle for carrying hay and grain, the said shelvings being in separate parts, and therefore capable of being put upon or removed from the wagon by one person without much trouble or labor.

A designates the top rail of a wagon-box. B are the cross-beams for supporting the planks or longitudinal strips. These cross-beams have grooves *a a* (see Fig. 2) cut in their under sides, of a shape to permit the top rail of the wagon-box to partially enter, and so as to insure the said cross-pieces resting firmly thereon. A metal yoke or clamp, *b*, is employed, which is so secured as to hold the

cross-beams firmly upon the wagon when the ends of the top rails of the box have been thrust between it and the cross-beams B; and a hook, *c*, is employed in each side, which sinks into a recess in the end rails, and prevents the cross-pieces B from moving out of place.

C designates the longitudinal strips or planks of the shelvings. The face of each of these planks C carries near each end a hook, *d*, the two hooks in each plank pointing in opposite directions; and these hooks are intended to hook into staples secured to the tops of the cross-beams B, as shown clearly in Fig. 3.

D are braces secured to each plank C in such manner that their lower ends will bear against the body or truck of the wagon, and thus serve as an additional support to the plank C at intermediate points of their length between the cross-beams B.

From the above description it will be seen that every part of the shelving is separate from the other, and thus the shelving is rendered more portable, and can be easily put upon and removed from a wagon-box by one person, which cannot be well done with shelvings as at present constructed, without considerable strength and a great deal of trouble.

What I claim as new, and desire to secure by Letters Patent, is—

1. Securing the cross-beams B to the top rail of the wagon, substantially as specified.
2. The manner of securing the planks C to the cross-beams B, substantially as described.
3. The employment of braces D for supporting the planks C between the cross-beams B, substantially as described.

GEO. R. CANNON.
